UNITED STATES PATENT OFFICE.

GERHARD SCHMITZ, OF BYESVILLE, OHIO, ASSIGNOR OF ONE-HALF TO
DAVID BARCLAY, OF BYESVILLE, OHIO.

AUTOMATIC SWITCH.

No. 846,147.

Specification of Letters Patent.

Patented March 5, 1907.

Application filed September 19, 1906. Serial No. 335,221.

To all whom it may concern:

Be it known that I, GERHARD SCHMITZ, a citizen of the United States, residing at Byesville, in the county of Guernsey and State of Ohio, have invented new and useful Improvements in Automatic Switches, of which the following is a specification.

This invention relates to automatic switches, and more particularly a switch for use in mines in which a main track is provided for the loaded cars and a siding for the empty cars. With this arrangement of tracks the empty cars are usually shunted to the siding by making a flying switch.

15 The present invention has for its object to improve and simplify the apparatus disclosed in Letters Patent of the United States granted to me July 17, 1906, No. 826,366.

20 In the accompanying drawing, Figure 1 is a plan view of the switch and its operating mechanism. Figs. 2, 3, 4, and 5 are side elevations showing the parts in different positions.

25 Referring specifically to the drawings, 10 denotes the rails of the main track, and 11 the rails of the siding. The movable switch-rails 12 are carried by the usual switch-bar 13, to one end of which is fastened a switch-closing spring 14. The other end of the 30 switch-bar extends under the outer rail of the main track and beyond said rail, the extremity of the bar being formed with an upstanding flange 15. Between this flange and the last-mentioned rail is a wedge-bar 16 for actuating the switch. The flange 15 carries a 35 friction-wheel 17, which engages the outer edge of the wedge-bar.

40 At 18 is indicated a trip-lever, which is located adjacent the outer rail of the main track on the outside thereof. This lever is in the path of the wheels of the locomotive or motor and actuates the wedge-bar, being connected thereto by a rod 19. The trip-lever is in the shape of a link and swings on 45 trunnions 20, extending from its sides and journaled in suitable bearings. The link is made heavier or weighted on one end, so that it will be normally in upright position. The end of the rod 19 next to the trip-lever is 50 formed into a loop 21, through which the top cross-bar 22 of the trip-lever extends, whereby a loose connection is had between said lever and the rod. The object of this loose connection will be explained hereinafter.

The normal position of the parts is as 55 shown in Figs. 1 and 2. In this position the switch is closed and the cross-bar 22 of the trip-lever is at the front end of the loop. If now a train is approaching the switch with the motor or locomotive in front and it is desired to make a flying switch, the motor is uncoupled a short distance in front of the switch and run ahead at increased speed. When the motor-wheel strikes the trip-lever 18, it is swung downwardly to the left, as 60 shown in Fig. 3, whereby the wedge-bar 16 will be pulled forwardly, which opens the switch to enable the cars to run into the siding. After the motor-wheels have passed the trip-lever it swings back to an upright 65 position, as shown in Fig. 4, its loose connection with the rod 19 permitting this movement. When the trip-lever assumes this last position, the cross-bar 22 will be at the rear end of the loop 21, so that when the motor is returning on the main track with 70 loaded cars and the motor-wheels strike the trip-lever and swing it to the right, as shown in Fig. 5, the wedge-bar will be pushed back to its original position to close the switch. 75 After the cars have passed the trip-lever it will again come to an upright position, with its cross-bar 22 at the front end of the loop 21. The parts are then restored to their normal position. (Shown in Figs. 1 and 2.) 80 I claim—

1. The combination with a switch-actuating member, of a car-actuated trip constructed to swing in either direction, means for automatically returning the trip to operative 90 position, and a connection between said trip and member for operating the switch when the trip is swung in either direction, and constructed to allow the return movement of the trip.

2. The combination with a switch-actuating member, of a car-actuated trip constructed to swing in either direction, means for automatically returning the trip to operative 95 position, and a loose connection between 100 said trip and member constructed to operate the switch when the trip is swung in either direction, and to permit the return movement of the trip.

3. The combination with a switch-actuating member, of a normally erect car-actuated trip constructed to swing in either direction, and a connection between said trip 105

and member to operate the switch when the trip is swung in either direction, and constructed to allow the return movement of the trip.

5. The combination with a switch-actuating member, of a looped rod loosely connected thereto, and a car-actuated trip constructed to swing in either direction to engage either end of the loop for operating the switch.

1c 5. The combination with a switch-actuat-

ing member, of a looped rod loosely connected thereto, and a normally erect car-actuated trip engageable with either end of the loop for operating the switch.

15 In testimony whereof I have signed my name to this specification in the presence of two subscribing witnesses.

GERHARD SCHMITZ.
